UNITED STATES PATENT OFFICE.

PATRICK KEEGAN, OF FALL RIVER, MASSACHUSETTS, ASSIGNOR TO DRAPER CORPORATION, OF HOPEDALE, MASSACHUSETTS, A CORPORATION OF MAINE.

FEELER MECHANISM FOR LOOMS.

Application filed November 11, 1925. Serial No. 68,369.

This invention relates to feeler mechanisms for looms whereby the operative condition of the loom is changed from time to time dependent upon the condition of the filling in the shuttle.

It is now the ordinary practice to provide looms with feeler mechanisms for effecting replenishment of filling when the filling in the active shuttle becomes substantially, but 10 not quite, exhausted, and much attention and skill has been exercised in the development of such mechanisms. Owing to the delicacy of such mechanisms and the necessity for their response to filling conditions in the 15 shuttle, it frequently happens that feeler mechanisms of some characters now in use prematurely call for a change of filling, and such premature call by the feeler for replenishment has been sought heretofore to 20 be avoided by providing the feeler with a lock which normally locks or holds the feeler from the performance of its function until the filling is substantially exhausted. In such cases, the feeler usually contacts with 25 the filling on detecting beats and when the filling is substantially exhausted or just prior thereto, the lock is actuated to unlock the feeler.

Where the feeler engages the filling on detecting beats and is mounted for side-slipping movement longitudinally of the shuttle, the tendency of the feeler to move sidewise on a detecting beat has an injurious effect upon the filling in the shuttle, especially 30 when the filling is of delicate character.

One of the objects of the present invention is to provide a feeler mechanism where in the feeler does not contact with the filling and is normally free to partake of its feeler 40 movements, and wherein a lock is provided which is normally unlocked from the feeler and is moved into locking relation therewith on each detecting beat until the filling is substantially exhausted, and thereupon 45 fails to be moved into locking engagement with the feeler, so that the feeler may perform its function and call for a change of filling.

The invention and the novel features and 50 new combination of parts will best be made clear from the following description and the accompanying drawings of one good form thereof.

In the drawings:

Fig. 1 is a perspective view of the feeler

side of a loom provided with the present invention and some of the loom parts being omitted for clearness of illustration;

Fig. 2 is a plan view with some of the parts broken away, showing the feeler mechanism of the present invention on an enlarged scale, and the relation of parts when a working supply of filling is present in the shuttle on a detecting beat;

Fig. 3 is a similar view to that of Fig. 2 showing the relation of parts when the filling is substantially exhausted on a detecting beat and the normally unlocked locking member fails to lock the feeler; and

Fig. 4 is a sectional elevation showing the 70 relation of parts of the feeler mechanism of the present invention when the filling in the shuttle is substantially exhausted on a detecting beat.

Feeler mechanisms are now usually employed to effect a change in the loom operation when the filling in the shuttle reaches a condition of substantial exhaustion but prior to complete exhaustion, and such change in the loom operation may be loom 75 stoppage or filling replenishment. In the present instance, the invention is shown and will hereinafter be described as associated with means for effecting replenishment of filling when the filling in the shuttle becomes 80 substantially exhausted. The replenishing mechanism itself and its details are not herein shown and described because such details form no essential part of the present invention, and, since they are now well understood in the art their description and illustration herein is unnecessary.

The loom frame 1 may be of the usual construction and has arising from the usual transverse or rock shaft an arm 2 to which is pivotally connected at 3 (Fig. 1) an actuator 4, to the rear portion of which is pivotally connected at 5 the arm 6, the rear end of which is adapted to be engaged by an operating member 7 secured to or formed as part of the usual cam follower. The transverse or rock shaft extends from one side of the loom to the other, as usual, and when it is rocked through the train of mechanism described, filling replenishment is effected.

Mounted upon the loom frame or shipper stand is the support 8 which may be secured in place adjustably by means of a bolt 9, and to the end portion of the support 8 is pivotally mounted a bell crank lever, the horizon-

tal arm 9^x of which extends under a finger or projection 10 mounted on the arm 6. The bell crank lever referred to is pivotally mounted at 11 on the support 8 and its downwardly extending arm 12 in the present instance is connected at 13 to a transmitter 14 constituted as a rod, the end of which remote from the bell crank lever is connected at 15 to a slide 16 mounted in bearings at 10 the rear of the feeler stand, as will presently appear.

Adjustably secured to the arm 17 extending from the shipper stand 18 is a bracket 19 which may be employed conveniently for 15 supporting the feeler stand 20. The feeler stand 20 may be adjustably secured in place by means of the bolt 21 and slot 22, Fig. 1.

The feeler 23 is herein shown as of the inclined type and the parts of the feeler mechanism thus far described are or may 20 be substantially the same as the corresponding parts shown and described in the patent to Edward S. Stimpson, No. 1,309,226, July 8, 1919. In the Stimpson patent the 25 feeler extends through a slot in the slide at the rear of the feeler stand, and the same condition is true in the present instance of the invention. In the Stimpson patent, also, the feeler is mounted for engagement with 30 the filling on detecting beats, but in the present invention the feeler does not engage the filling, as will more fully appear.

The feeler 23 has the forwardly extending stem portion 24 which passes through a 35 swivel block bearing 25 at the front of the feeler stand, similar to the like swivel block of the Stimpson patent, and between the swivel block 25 and the bridge 26 secured to the feeler is interposed a spring 27 normally tending to move the feeler into its 40 rearward feeling position, at which time the bridge 26 which rests upon the feeler stand, contacts with the rear bearing portion of the feeler stand and thereby limits the rearward movement of the feeler. With the 45 exception that the feeler in the present invention does not contact with the filling and in some other respects to be hereinafter described, the mechanism hereinbefore 50 described may be substantially the same as that more fully described and shown in the Stimpson patent to which reference has been made.

The lay 28 is provided with the usual 55 shuttle box, the front wall of which has an opening 29 which registers with a corresponding opening 30 in the front wall of the shuttle 31 when the shuttle is in the shuttle box, as indicated in Fig. 1. The construction 60 of the lay and shuttle in these respects may be as usual.

In accordance with the present invention, 65 the feeler does not contact with the filling on detecting beats and is normally unlocked or free to partake of its side-slipping move-

ment, and in connection with such feeler the present invention contemplates a locking member which is normally unlocked from the feeler but which is moved into locking engagement with the feeler on each detecting beat until the filling is substantially exhausted, and thereupon the lock or locking member fails to engage the feeler and the latter is freed to its side-slipping movement. In this aspect it will be noted that the feeler lock differs fundamentally from feeler locks heretofore used which normally lock the feeler from side-slipping movement and free the feeler only when the filling is substantially or nearly exhausted.

Mounted in bearings pivotally carried by the feeler stand is the feeler lock, the rear end portion of which extends rearwardly beyond the end of the feeler and is engaged by the filling in the shuttle on each detecting beat. The feeler lock, in the present instance, comprises a sliding member 32 which is movable towards and from the front of the loom in the rear and front bearings 33 and 34 respectively. The rear end bearing may be conveniently formed by a cap piece 35 overlying the edge of the slide locking bar 32. The front portion of the slide 32 is preferably formed as a stem 36 about which is the light spring 37, the front end of which rests against the bearing 34, and the rear end of which rests against an adjustable collar or nut 38 secured to the locking slide 32, the construction being such that the spring 37 normally tends to move the lock into its rearward position, and yet permits the lock to be moved forwardly. The rear end portion of the lock extends rearwardly beyond the end of the feeler 23, as indicated in Fig. 1, and such rearwardly 105 extending portion 39 has a laterally extending end 40, the rear surface of which is designed to be engaged by the filling on detecting beats. In the present instance, the rear end 40 which extends over the rear end of the feeler 23, is provided with a cushioned filling-contacting portion 41 which may be made of any suitable yielding material that will not injure the filling by contact therewith on a detecting beat.

The front surface 42 of the lock is shown as provided with a shoulder 43, which is normally rearward of the end of the feeler, as shown in Fig. 2 by dotted lines, when the feeler and feeler lock are in their normal undisturbed position. When, however, the rear end of the lock is engaged by a working supply of filling in the shuttle on a detecting beat, the lock is pushed forwardly until the surface 42 engages the rear end of the feeler, whereupon the feeler tends to sideswipe but is prevented from doing so by the shoulder 43, as indicated in Fig. 2. In Fig. 2 the filling carrier 44 has a working supply of filling 45 wound thereon, and the ac- 130

tion above described will continue until the filling approaches substantial exhaustion. That is, the normally unlocked feeler will be locked by forward movement of the locking member when such member engages a working supply of filling in the shuttle on a detecting beat, but will fail to be engaged by the locking member when the filling is substantially exhausted on a detecting beat, thereby, in the latter case, permitting the feeler to partake of its side-slipping movement to call for replenishment of filling as will now be explained.

The feeler 23 has a lug 46 extending therefrom, and threaded into this lug is the stem 47, the rear end 48 of which constitutes a bunter for engagement with a surface on the lay when the feeler lock fails to be moved forwardly on a detecting beat by a working supply of filling in the shuttle, so that the feeler at such times is free to partake of its side-slipping movement, as indicated in Fig. 3, and call for a change of filling.

The bunter 48 is preferably adjustable towards and from the rear end of the feeler by means of the screw-thread connection between the stem 47 and the projection 46, and the parts may be locked in their adjusted position by the lock nut 49. The bunter 48 is herein shown as engaging the front wall of the shuttle when the feeler lock fails to be moved forwardly by a working shuttle of filling in the shuttle, to lock the feeler, and under such conditions, since the shoulder 43 of the lock is rearward of the extreme rear end of the feeler, the bunter 48 may slide along the wall of the shuttle freely and call for a change of filling. Of course the bunter 48 might engage any other convenient surface on the lay, but either the wall of the shuttle or the shuttle box presents a convenient engaging surface.

When a working supply of filling is present in the shuttle on a detecting beat and the feeler and feeler lock are in their normal rearward feeling position, as indicated in Fig. 1 and by dotted lines in Fig. 2, the feeler is unlocked, and becomes locked only as the feeler lock itself is moved forwardly by the working supply of filling in the shuttle and the parts assume the position of the full lines, Fig. 2. When, however, the filling is substantially exhausted on a detecting beat, as in Fig. 3, the feeler lock will not be moved forwardly sufficiently far to engage the rear end of the feeler before the bunter 48 on the feeler engages the side wall of the shuttle and shuttle box, and since the feeler is then unlocked, side-swipe movement of the feeler can take place to call for replenishment of filling.

What is claimed is:

1. In a feeler mechanism for looms, the combination of a side slipping feeler normally free to partake of its side slipping

movement, a feeler lock which is normally unlocked from the feeler to permit said side slipping movement and having a part which is moved relative to the feeler into locking engagement with the feeler by a surface within the shuttle on each detecting beat when a working supply of filling is present in the shuttle, and which fails to be moved into locking engagement with the feeler by the surface within the shuttle when the filling is substantially exhausted on a detecting beat, and means actuated by side slipping movement of the feeler to effect replenishment of filling.

2. In a feeler mechanism for looms, the combination of a feeler mounted for movement longitudinally of the shuttle to call for replenishment of filling and normally free to partake of such movement, a feeler lock which is normally unlocked from the feeler when the feeler and feeler lock are in their normal rearward position and which is moved forwardly relative to the feeler by the filling into locking engagement on each detecting beat except when the filling is substantially exhausted, and thereupon remaining unlocked from the feeler that the latter may move longitudinally of the shuttle.

3. In a feeler mechanism for looms, the combination of a side swipe feeler normally unlocked for side swipe movement, a lock which is moved into locking engagement with the feeler on each detecting beat until substantial exhaustion of filling whereupon it fails to be moved into locking engagement with the feeler that the latter may side swipe, and means carried by the feeler to slide longitudinally of the shuttle box with the feeler on substantial exhaustion of filling.

4. In a feeler mechanism for looms, the combination of a feeler mounted for movement longitudinally of the shuttle to call for replenishing of filling, a feeler lock which is unlocked from the feeler when the lock and feeler are in normal rearward feeling position and is moved into locking engagement with the feeler by the filling on a detecting beat until the filling is substantially exhausted, and means carried by the feeler for sliding along a surface on the lay when owing to such exhaustion of filling the lock fails to engage and lock the feeler.

5. In a feeler mechanism for looms, the combination of a side slipping feeler which does not engage the filling, a feeler lock extending rearwardly for engagement with the filling and normally out of locking engagement with the feeler but moved into locking engagement therewith on a detecting beat until the filling is substantially exhausted and thereupon remaining unlocked on that detecting beat to permit side slipping movement of the feeler to call for replenishment of filling.

6. In a feeler mechanism for looms, the

combination of a feeler mounted for side slipping movement, a feeler lock extending rearwardly of the feeler for engagement with the filling and normally out of locking engagement with the feeler but moved into locking engagement therewith on each detecting beat until the filling is substantially exhausted and thereupon remaining unlocked to permit side slipping movement of the feeler to call for replenishing of filling, and a part carried by the feeler for side slipping engagement with the shuttle when the lock fails to be moved into locking engagement with the feeler on a detecting beat.

7. In a feeler mechanism for looms, the combination of a side slipping feeler normally free to partake of its side slipping movement to effect replenishing of filling, a feeler lock which is normally unlocked from the feeler and having a part which is moved into locking engagement with the feeler when the feeler lock is moved forwardly on a detecting beat by a working supply of filling but which fails to engage the feeler when the filling is substantially exhausted on a detecting beat, and means actuated by side slipping movement of the feeler to effect replenishing of filling.

8. In a feeler mechanism for looms, the combination of a side slipping feeler which does not engage the filling, a feeler lock which engages the filling on each detecting beat and by its forward movement relative to the feeler locks the feeler from side slipping movement until the filling is substantially exhausted and thereupon fails to engage the feeler as the lock is moved forwardly that the feeler may side slip and call for a change of filling.

9. In a feeler mechanism for looms, the combination of a side slipping feeler which does not engage the filling, a feeler lock having an end extending rearwardly beyond and across the end of the feeler which engages the filling on each detecting beat and by its forward movement relative to the feeler locks the feeler from side slipping movement until the filling is substantially exhausted and thereupon fails to engage the feeler as the lock is moved forwardly that the feeler may side slip and call for a change of filling.

10. In a feeler mechanism for looms, the combination of a side slipping feeler which does not engage the filling, a feeler lock having a filling engaging end extending across the end of the feeler and provided with a shoulder which prevents side slipping movement of the feeler when the feeler lock is moved forwardly by a working supply of filling on a detecting beat but fails to engage the feeler when the feeler lock is moved forwardly by a substantially exhausted amount of filling.

11. A feeler mechanism for looms, comprising a side slipping feeler which does not engage the filling, a feeler lock having a filling engaging end extending across the end of the feeler and provided with a shoulder to lock the feeler from side slipping movement except when the filling is substantially exhausted on a detecting beat, and means actuated by the side slipping movement of the feeler to effect replenishment of filling.

In testimony whereof, I have signed my name to this specification.

PATRICK KEEGAN.
